CONTAINER

Richard J. White, New York, N. Y., assignor to
 American Can Company, New York, N. Y., a
 corporation of New Jersey

Application September 28, 1939, Serial No. 296,981

2 Claims. (Cl. 221—62)

The present invention relates to dredging cans for powders, condiments and the like and has particular reference to a fully sealed rectangular can which is opened by breaking out scored parts cut in a central panel of the can end or top, this panel having a depressed rectangular section, two opposed straight sides of which are folded over to provide spaced oppositely disposed straight channels and overhanging ledges forming slide seats for a flat slide member which has a curled and slotted edge by means of which the can may be fully opened for dispensing of its contents as in removal by a spoon, or the dispensing may be done by sifting the contents through the slotted curled edge of the slide member which at such a time acts as dredge openings, they being in alignment with the opening formed in the can at the time the scored parts of the can top are broken through in initially opening the can and still another position of the slide member provides a reclosure for the can.

An object of the present invention is the provision of a rectangular can of the dredging can type which is initially sealed on its contents and which may be opened to make effective a flat slide member which has sliding movement within the depressed rectangular panel section of a flat can top, opposite walls of this depressed panel having channels formed beneath retaining ledges which hold the slide member within the depression but allow for free movement of the slide, different positions of which determine the type of dispensing of the can contents, one position effecting a reclosure of the can.

Another object is the provision of a rectangular dredging can of the character described wherein the slide member has its edges curled to provide easy actuation, a curled edge also functioning as a sifter and disintegrator member when the contents of the can are dispensed by sifting.

Still another object is the provision of positioning elements for such a dredging can whereby each position of the slide may be accurately determined.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a can embodying the present invention, the view showing the top slide member in fully closed position;

5 Figs. 2, 3 and 4 are top plan views of the can showing the three different positions of the slide member, Fig. 2 being the open position which allows for initially breaking out of the scored area of the top, Fig. 3 being the reclosed position and Fig. 4 showing the sifter position; and

10 Figs. 5 and 6 are longitudinal and transverse sections drawn to a larger scale being taken respectively along the section lines 5—5 and 6—6 in Figs. 3 and 4.

15 The present invention is concerned with the dredging can having a simple one-piece perforated top slide arranged for movement across a flat wall of a sunken panel provided in the can top, such a slide having a manipulating slotted and curled edge which functions in one position of the slide as a sifting or dredging feature and which at the time provides a finger piece for manipulating the slide into various positions. 20 The slide becomes effective to condition the can for dispensing of or for enclosing its contents after the can has been initially opened, by breaking out a scored part of the top end in the panel wall. Opposed side walls of the sunken panel 25 are parallel and are formed with straight channels and overhanging ledges which retain the slide in close contact with the can top in all positions of the slide.

20 Such a can is disclosed in the drawing as being 30 rectangular and is preferably formed of metal. The can body is designated by the numeral 11, Fig. 1. Such a can is provided with an imperforate bottom end member 12 and an imperforate top end member 13. The two end members may be secured to the body in conventional double or other type of seams 14.

35 The top end 13 is primarily of the usual dished form required for double seaming but its central depressed wall, designated by the numeral 15, is further depressed in a central sunken panel 16. This depressed panel 16 is rectangular in shape and two opposed side walls are bent over or collapsed, as illustrated in Fig. 5, to form opposed channels 17 located under overhanging ledges or shoulders 18. Such channels and ledges provide guideways for the slide and in the manufacture of the can are preferably formed after the slide has been placed in position or assembled with the can top.

40 A flat slide member 21 is used for this purpose and after the parts have been assembled and the channels and ledges have been formed, this slide may be moved back and forth from one side of the sunken panel 16 to the other. During this 45 movement the opposite ends of the slide ride along 50

55 the ledges 18 and the channels 17. The slide member 21 is provided with a slotted and curled edge 22 which is effective to sift the contents of the can when the slide is moved to the position shown in Fig. 4.

and are retained within the channels 17, the overhanging ledges 18 holding the slide down against the wall of the panel at all times.

Such a slide is preferably formed with two curled edges, a short curl 22 and a longer curl 23 disposed on opposite sides longitudinally of the slide. The long curl 23 extends substantially from one to the other of the ledges 18 of the can top. This curl is slotted as at 24. When slide 21 is moved, either of the edge curls 22 or 23 may be engaged by the fingers, the natural way of manipulating the slide being to draw it forward into the desired position.

The sunken wall part 16 of the panel is preferably cut or scored either partially or entirely by an arcuate score line 25 the ends of which are joined by a broken score line 26. The line 26 extends longitudinally of the can top and as best shown in Fig. 3 is substantially in the center of the can end.

When the can is received by the ultimate consumer it is fully sealed and the top 13, containing the score lines 25, 26, forms an imperforate wall member for the can. The slide in such position is against one long side of the sunken panel 16, this being the position illustrated in Fig. 1. To initially open the can so that its slide 21 may be effective, the edge curl 23 is preferably engaged by the fingers and is drawn toward the opposite wall of the sunken panel or into the position shown in Fig. 2. The long side of the slide adjacent the curl 23 strikes against the vertical wall of the sunken panel and this definitely locates the slide for its opening position.

The score line 25 is thus exposed and the initial opening of the can may be had by merely breaking through the top wall along the score line 25. In doing this the removable part of the top, designated by the numeral 21 which is the area confined within the score lines 25, 26, is preferably pushed down into the can, the part 21 bending along the broken score line 26. Such a position is illustrated in Fig. 6. This leaves a dispensing opening 28 in the wall of the panel 16. The opening as herein shown is made circular along one side so that a spoon may be inserted into the container and the spoon load then scraped level along the straight edge of the opening. In this way a relatively large quantity of the contents may be removed by this means.

In the event that it is desired to sift the contents of the can in the dispensing operation, the slide 21 may be grasped by the short curl 22 and drawn over to the opposite side of the sunken panel. This is the same position it formerly occupied, Figs. 4 and 6 illustrating the sifter position of the slide. In this position the slots 24 of the curled edge 23 are directly over and just inside of the straight edge of the dispensing opening 28. When the can is inverted as in sifting position, therefore, the contents are caused to pass through the slots 24.

In such passage the curled shape of the edge part 23 acts as a disintegrator and this breaks up and more thoroughly sifts the contents as it is being dispensed. In this position of the slide the long side adjacent the curl 22 is against the long vertical wall of the sunken panel 16. This vertical wall thus provides a definite stop, thus limiting movement of the slide to an exact predetermined position.

When the can is to be reclosed, it is merely necessary to draw back on the slide 21 to bring it into the intermediate position shown in Fig. 3. The slide now completely covers the discharge

opening 28 and the overhanging ledges 18 of the can top, which are at all times pressing against the ends of the slide, movably hold the slide into flush contact with the can top. This prevents undesirable sifting or leaking of the can contents when the closed can is being handled.

Provision is made for definitely locating such a closing position of the slide. For this purpose the panel wall of the top is pressed downwardly in a pair of spaced protuberances 31 (Figs. 2 and 5). In like manner the slide 21 is also provided with a pair of spaced protuberances 32. In the other positions of the slide the protuberances 32 merely spring over the panel wall and have no effect as stops. In the closing position, however, the protuberances 32 engage the protuberances 31, as best shown in Fig. 5, and this securely locks the parts together.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A dredge top can comprising a top end having a rectangular depression two opposite walls of which are formed with straight channel sections and overhanging ledges, score lines cut in the panel wall of said depression and setting off a removable part which when removed from the plane of the end by separation along said score lines opens the can while forming a dispensing opening, and a flat slide member located in said depression and having close engagement with its panel wall while extending into said channels at two opposite ends and being held in sliding position by said overhanging ledges, said slide having a slotted edge curl extending between said ledges whereby the slide may be moved over said dispensing opening, said curl when aligned over the dispensing opening providing for sifting of the can contents, other positions of said slide member further opening or reclosing the can.

2. A dredge top can comprising a top and having a rectangular depression, two opposite walls of which are formed with straight channel sections and overhanging ledges, curved and straight score lines cut in the panel wall of said depression and setting off a removable part of segmental shape which when removed from the plane of the end by separation along the curved section of said score lines opens the can by bending the removable part along the straight section of the score while forming a dispensing opening into which a spoon may be inserted, for removing the can contents, a flat rectangular slide member located in said depression and having close engagement with its panel wall while extending into said channels at two opposite ends and being held in sliding position by said overhanging ledges, said slide having edge curls on its two sides whereby the slide may be moved over said dispensing opening, one of said edge curls being slotted and when aligned over the dispensing opening providing for sifting of the can contents, other positions of said slide member further opening or reclosing the can, and stop elements formed in said slide and in said panel wall for determining the can reclosing position.
